UNITED STATES PATENT OFFICE

EUSTACE CREEES AND CHARLES S. COURT, OF PROVIDENCE, RHODE ISLAND,
ASSIGNORS TO GEORGE K. WEBSTER, OF NORTH ATTLEBOROUGH, MASSACHUSETTS.

DESIGN FOR A BACK FOR BRUSHES OR SIMILAR ARTICLES.

SPECIFICATION forming part of Design No. 29,216, dated August 16, 1898.

Application filed July 23, 1898. Serial No. 686,739. Term of patent 7 years.

To all whom it may concern:

Be it known that we, EUSTACE CREEES and CHARLES S. COURT, of Providence, in the county of Providence and State of Rhode Island, have invented a new and useful Design for the Backs of Brushes or Similar Articles, of which the following is a specification, reference being had to the accompanying drawing, which forms part of the same.

10 In the drawing the figure is a plan view of the back of a brush or hand-mirror containing our design.

A is the back, and B is the handle, of the article ornamented.

15 The ornamentation of the handle B begins with a shield C in the center of the base and surmounted by a group of flowers D and surrounded by scrolls E, which terminate in a right and left scroll F, with the leaf ornament G above and below the same. From the bottom of the right and left scrolls F there extends around the edge of the handle B a row of graduated beads H. Above the right and left scrolls F there is arranged a large shell I, and extending from the opposite edges of said shell are two long scrolls J along the opposite edges of the back, and above said scrolls J are shorter scrolls K along the up-

per edge of the back, and between said scrolls K and J there is a bead L on each side. Between the upper scrolls K there is a bead M on the upper edge of the back. Inclosed by said scrolls is a gadroon border M', extending from the shell I to the top of the brush and terminating in another circular shell N, 35 with a group of flowers O in the center of the same. On the inside of the gadroon border M' there is a line P on each side, with a leafy scroll Q at the upper end. The opposite lines P inclose an arrangement of light scrolls R 40 and flowers S, which surround a high dome center shield T.

What we claim as our invention, and desire to secure by Letters Patent of the United States, is—

45 The design for the back of a brush or similar article substantially as herein shown and described.

In witness whereof we have hereunto set our hands this 18th day of July, 1898, in the presence of two subscribing witnesses.

EUSTACE CREEES.
CHARLES S. COURT.
